[57] CLAIM

The ornamental design for a basketball shaped beverage container, as shown and described.

DESCRIPTION

FIG. 1 is a perspective view showing the basketball shaped beverage container having a flattened bottom and an extendable sports cap at its top;

FIG. 2 is a top view of the basketball shaped beverage container shown in FIG. 1;

FIG. 3 is a side elevational view of the basketball shaped container shown in FIG. 1; and,

FIG. 4 is a perspective view similar to FIG. 1 showing the sports cap in its extended position.
